BUFFING MECHANISM FOR CAR-PLATFORMS.

1,086,573.

Specification of Letters Patent. Patented Feb. 10, 1914.

Application filed November 6, 1911. Serial No. 658,813.

To all whom it may concern:

Be it known that we, CHARLES T. WESTLAKE and CHARLES F. FREDE, citizens of the United States, residing at St. Louis, Missouri, have invented a certain new and useful Improvement in Buffing Mechanism for Car-Platforms, of which the following is a full, clear, and exact description, such as will enable others skilled in the art to which it appertains to make and use the same, reference being had to the accompanying drawings, forming part of this specification, in which—

Figure 1 is a top plan view of a cast metal platform with portions of the buffer beam and end sill, and showing the buffing mechanism in position thereon. Fig. 2 is a longitudinal section taken approximately on the line 2—2 of Fig. 1 with the buffing gear detached from the platform. Fig. 3 is a transverse section taken on line 3—3 of Fig. 1.

This invention relates generally to railway car platform construction, and more particularly to the buffing mechanism applied to cast metal platforms such as are now in general use in passenger car construction, and the principal objects of the invention are to construct the skeleton platform and buffer beam so that a form of buffing mechanism now in use on a number of passenger cars, and of a type accepted by the M. C. B., can be readily applied to the platform and buffer beam, and further to provide a construction wherein the operating parts of the buffing mechanism can be readily placed in or removed from position without detaching the vestibule or the buffer beam from its stems, thereby permitting the buffing mechanism to be easily and quickly repaired when any of the operating parts have become broken or unfit for service.

With the above objects in view our invention consists in certain novel features of construction and arrangement of parts hereinafter more fully described and claimed.

Referring to the accompanying drawings, the numeral 1 designates the end sill of a cast metal car underframe of the type now in general use, and formed integral with and projecting forwardly from the central portion thereof is a pair of vertically disposed walls 2 on the upper and lower edges of which are provided with laterally pro-

jecting strengthening flanges 3, and formed integral with the lower edges of said walls and connecting the same in a horizontally disposed plate 4. Formed integral with the sill 1 and projecting forwardly therefrom at the sides of the plates 2 is a pair of vertically disposed webs 5, and formed integral with the upper edges thereof are inwardly projecting flanges 6. Formed integral with or rigidly fixed to the forward ends of the plates 2 and webs 5 is a buffer beam 7 of the usual box shape, and located on top of the central portion of this buffer beam is a threshold plate 8.

The numeral 9 designates a buffing member of the usual type positioned in front of the beam 7, and positioned on top of the buffer 9 is a plate 10 which is adapted to slide beneath the threshold plate 8. The buffer 9 is carried by the forward ends of a pair of side buffer stems 11 and the central portion of said buffer bears against the forward end of a center buffer stem 12. All of the buffer stems are arranged to slide freely through corresponding openings 13 formed through the front and rear walls of the buffer beam 7. The front portions of the side buffer stems 11 are preferably square or non-circular in cross section, and the rear portions of said side stems which occupy positions within the skeleton platform comprising the plates 2 and webs 5 are preferably round in cross section, and extreme rear ends of said rounded portions slide through suitable bearings formed in transverse plates 14 which latter are formed integral with the plates 2 and webs 5. Formed integral with the upper edges of these transverse plates 14 are horizontally disposed flanges 14^a which occupy the same horizontal plane with and are practically continuations of the horizontally disposed flanges 3 and 6. All of the flanges 3, 6, and 14^a occupy the same horizontal plane with the top plates of the end sill and buffer beam and thus the top of the entire casing is smooth and devoid of projections which would interfere with the flooring laid on top of the platform casing. Located upon these side stems and bearing against the shoulders formed between the non-circular forward portions and rounded rear portions are follower plates 15, and bearing against said follower plates are the forward ends of side

buffer stem springs 16, the rear ends of which bear against the transverse plates 14. Formed integral with the plates 2 and 4 and projecting inwardly from the inner faces of the plates 2 are vertically disposed webs 17 which are located a short distance from the rear wall of the buffer beam 7, and formed integral with the front sides of these webs and with the corresponding portions of the plates 2 are horizontally disposed brackets 18 which are perforated so as to receive bolts or rivets. Vertically disposed webs 19 which are counterparts of the webs 17 are formed integral with the rear portions of the webs 2 a short distance in front of the end sill 1, and formed integral with the rear sides of these webs and with the plates 2 are horizontally disposed brackets 20 which are perforated so as to receive bolts or rivets. The pairs of vertically disposed webs 17 and 19 form stops or bearings for the ends of a pair of plates 21 which form a part of the buffering gear located within the pocket between the walls 2, and the inner faces of these plates 21 are inclined or beveled, and bearing thereagainst are the beveled or inclined side faces of a pair of plates 22. Bearing against the plates 22 are two sets of curved leaf springs 23, and positioned between said springs is a spacing block 24.

The numeral 25 designates a follower plate which bears against the forward ends of the plates 22, springs 23 and block 24, and formed integral with said follower plate 25 is a cylindrical housing 26 in which is seated one end of a compression spring 27. The forward end of this compression spring carries a front follower plate 28 which bears directly against the rear end of the center buffering stem 12. A rear follower plate 29 bears against the rear ends of the plates 22, springs 23 and block 24, and interposed between said follower plate 29 and the front wall of the end sill 1 is one or more compression springs 30.

The buffering gear just described is of a well known type, accepted by the M. C. B., and after this gear has been inserted in the pocket between the walls 2 a cover plate 31 is positioned over the greater portion of said gear, and said cover plate is held in position by means of rivets or bolts which engage in the perforated brackets 18 and 20. The brackets 18 and 20 besides providing means for attaching the cover plate 31 materially strengthen and reinforce the webs 17 and 19 that form stops or bearings for the plates 21.

Under normal conditions the expanded side buffer springs 16 hold the buffer 9 at its outer limit of movement, as shown in Fig. 1, and during the coupling of two cars the buffer 9 is moved inward toward the beam 7, and as a result, all of the buffer stems are likewise moved inward, thereby simulta-

neously compressing the side buffer springs and the compression spring 27. When the front follower plate 28 bears against the forward end of the cylindrical housing 26 said housing and the plate 25 will be moved rearwardly thereby moving the plates 22 rearwardly and at the same time toward one another by reason of their engagement with the inclined faces of the plates 21, and as said plates 22 are moved toward one another the leaf springs 23 will be engaged and at the same time the spring 30 will be compressed by reason of the rearward movement of the follower plate 29. Thus the side buffer springs 16 and spring 20 are compressed during the coupling operation and after such operation is completed, the heavy buffer springs and friction mechanism come into operation to absorb buffing stresses between the coupled cars.

By our improved construction which is comparatively simple and can be readily manufactured the skeleton platform and buffer beam are arranged to readily accommodate an accepted form of buffering gear, and thus the platform and buffering gear are combined to provide a very strong and serviceable construction, and the various parts of the buffering gear can be easily and quickly placed in proper position upon the beam and platform or removed therefrom without detaching the vestibule or the buffer from its stems, and thereby said construction is especially advantageous and desirable when it is necessary to make repairs or to renew any parts which have become worn or broken in service.

It will be readily understood that minor changes in the size, form and construction of the various parts of our improved buffering mechanism can be made and substituted for those herein shown and described without departing from the spirit of our invention, the scope of which is set forth in the appended claim.

We claim:

In a buffering mechanism of the class described, the combination with an integral one piece structure, comprising an end sill, a buffer beam, a pair of vertically disposed walls integral with and connecting the central portions of the buffer beam, and end sill, which walls are spaced apart to form a center buffering gear pocket, an imperforate bottom plate integral with the lower portions of said walls, outwardly projecting flanges integral with the upper edges of said walls, which flanges occupy the same horizontal plane with and are practically continuations of the top plates of the end sill and buffer beam, pairs of stop lugs integral with and projecting inwardly from said walls, horizontally disposed lugs integral with said walls behind the stop lugs, which horizontally disposed lugs are perforated to receive

fastening devices, a cover plate positioned over the center buffing gear pocket, a pair of side walls, spaced apart from the first mentioned pair of walls, flanges integral with and projecting inwardly from said side walls, which last mentioned flanges occupy the same horizontal plane with and are practically continuations of the top plates of the end sill and buffer beam, transversely disposed webs integral with and arranged between the side walls and the first mentioned pair of walls, which webs are provided with bearings for the side buffer stems, and horizontally disposed flanges integral with the upper ends of the transversely disposed webs, which last mentioned flanges occupy the same horizontal plane with and are practically continuations of the flanges on the upper edges of the longitudinally disposed webs, of a center buffing gear positioned in the pocket between the central pair of walls, parts of which buffing gear normally engage against the stop lugs on said walls, side buffing stems operating through the buffer beam and the transversely disposed webs, a center buffing stem operating through the buffer beam and coöperating with the center buffing gear, and a buffing member co-operating with the outer ends of said buffer stems.

In testimony whereof we hereunto affix our signatures in the presence of two witnesses, this 28th day of October, 1911.

CHARLES T. WESTLAKE.
CHARLES F. FREDE.
